US0D1026171S

(12) **United States Design Patent** (10) **Patent No.:** **US D1,026,171 S**
(45) **Date of Patent:** **** May 7, 2024**

(54) **MISTING DEVICE**

(71) Applicant: **O2COOL, LLC**, Chicago, IL (US)

(72) Inventor: **Wai Kwok Wu**, Hong Kong (CN)

(73) Assignee: **O2COOL, LLC**, Chicago, IL (US)

(**) Term: **15 Years**

(21) Appl. No.: **29/830,192**

(22) Filed: **Mar. 10, 2022**

(51) **LOC (14) Cl.** **23-01**

(52) **U.S. Cl.**

USPC **D23/225**; D23/213

(58) **Field of Classification Search**

USPC D23/224, 225, 226, 356, 357, 358, 359,
D23/360, 361, 362, 363, 200, 213, 314,

(57) **CLAIM**

The ornamental design for the misting device, as shown and described.

DESCRIPTION

FIG. 1 is a first perspective view of the misting device showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a second perspective view thereof.

The broken lines immediately adjacent the shaded areas represent the bounds of the claimed design while all other broken lines are directed to portions of the misting device. The broken lines form no part of the claimed design.

1 Claim, 7 Drawing Sheets
